THREAD SUPPORTING AND TENSIONING
ATTACHMENT FOR EMBROIDERY MA-
CHINES

Joseph C. Orrigo, New York, N. Y.

Application May 23, 1947, Serial No. 749,916

3 Claims. (Cl. 112—254)

1

This invention relates to an attachment for Bonnaz embroidering machines and particularly to means for feeding an additional yarn thread to the stitching mechanism to permit the use of twin threads by it.

One of the objects of the invention is to provide a yarn spindle, a tensioning guide, and a spring loop, arranged to guide the movement of the additional yarn thread to the vertical tube through which the yarn is delivered to the stitching mechanism of the Bonnaz machine.

Another object of the invention is to provide the combination so that maximum service efficiency may be obtained and by which the yarn thread will be kept in a controlled path of movement from the yarn spool to the delivery tube, regardless of the height of the take-off of the yarn thread from its supply spool.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevation of a Bonnaz machine, showing the position of the attachment for feeding the additional thread to the stitching mechanism thereof.

Fig. 2 is a perspective view of the yarn support and the tensioning guide.

Fig. 3 is a detail vertical sectional view through the screw post which supports the spring thread loop.

Fig. 4 is a vertical sectional view showing various size yarn spools attached on corresponding holding sleeves and support.

Fig. 5 is a perspective view of the various holding sleeves and support.

Referring to the drawing, which illustrates the practical embodiments of the invention, 10 designates the table of a Bonnaz machine, having a machine head 11, and thread looper contained by the box or housing 12.

Above the table 10 a thread board 13 is supported on the vertical tube 14, and held against turning at any desired position by means of a set screw 14a. The lower end of the vertical tube 14 is adjustable in the base block 15, which is provided with a set screw 16 for clamping the tube 14 in any adjusted position. The lower end of the tube 14 extends through an opening formed in the table 10, so that thread may be delivered through the tube to the housing 12 of the thread looper under the table 10.

2

On the yarn board 13, a yarn cone support stud 17 is mounted as by its base 18, and on this support stud and base, the cone 19 carrying the yarn 19a is positioned. The thread T of this spool 5 is conducted through the loop 20 of the overhead spring arm 21, which is also formed with an additional thread loop 22, through which the thread T is conducted to pass into the upper open end of the vertical tube 14, and through the tube to the housing 12 of the thread looper.

In addition to the yarn cone support stud 17, there is provided an additional yarn spindle 23, for double yarn stitching, which is supported on the yarn board 13 by means of its base 24. On 15 this spindle, the sleeve 25 freely turns. The sleeve 25 is formed with an integral disc 25a and a short tubular bottom extension 25b. On this sleeve and disc, the yarn spool 26 is mounted to spin on the spindle. For different size yarn spools, additional 20 sleeve attachments are provided, for example, for the larger yarn spool 26' a larger sleeve 25' is furnished. For a still different yarn spool 26'' a still different sleeve 25'' is provided.

The yarn thread 26a is conducted from the spool 26 through the vertical space 27 of the tensioning guide 28. The space 27 is constituted by means of the vertical bars 28 and 29. The lower ends of the vertical bars are secured to the base block 31, and this block is provided with a screw 32, which is extended through the yarn board 13, and clamped in place as by a wing nut 33, threaded thereon.

The base block 31 is adjustable so that the relation of the vertical bars 28 and 29 to the base 35 board 12 may be varied to modify the friction of these bars to the movement of the yarn thread. The vertical length of the bars 28 and 29 equals the total length of the yarn spool or exceeds it.

The yarn thread 26a after passing out of the 40 space 27 enters the wire loop 34, which is supported on the spring wire post 35. The post 35 is secured to the yarn board 13, by means of a vertical screw 36 and the clamping nut 37, see Fig. 3.

45 From the wire tensioning loop 34 the yarn thread 26a is conducted into the open upper end of the tube 14, and passes through the lower end of this tube under the table 10 and enters the housing 12 of the thread looper, where it is fed to the stitching mechanism, and used with the primary thread T.

50 My invention thus provides means for supplying an additional thread to the stitching mechanism of the Bonnaz machine, whereby an increased variety of work may be performed by the machine so equipped.

The attachment is easily made to a standard Bonnaz machine, and will continue to provide satisfactory service for the life of the machine and will not require more than the normal attention to keep it in good service.

It is to be understood that with this attachment the yarn will unwind in full view of the operator and as the end of the yarn approaches, the operator can replace the unwound spool with a full spool, tie the ends together and pull the new yarn through into operating position, thereby eliminating the rethreading of the machine with each new spool.

This device is attached on the Bonnaz machine table, directly in the back of the machine head. The bars 28 and 29 are used as an adjustable tension means whereas the looped spring is provided merely to absorb the unevenness of pull caused by imperfectly wound yarns and the sudden starts of the machine.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an embroidery machine having a base, a head supported on said base, a vertical hooked needle reciprocably mounted in said head, a thread looper disposed beneath said base and a thread spool mounting board supported above said head, that improvement which comprises the provision of means for supporting a spool of thread on said board adjacent one end thereof, guide means for guiding the thread from said spool to said thread looper, said guide means providing the support for said mounting board, thread tension means mounted on said board intermediate said guide means and said spool supporting means, said tension means comprising a pair of vertically extending bars for engaging opposite sides of said thread, means for adjusting the relative position of said bars with respect to the direction of the movement of said thread between said bars whereby the tension on said thread may be adjusted, and means for holding the mounting board in a desired adjusted position on said guide means with relation to the base.

2. In an embroidery machine having a base, a head supported on said base, a vertical hooked needle reciprocably mounted in said head, a

thread looper disposed beneath said base and a thread spool mounting board supported above said head, that improvement which comprises the provision of means for supporting a spool of thread on said board adjacent one end thereof, guide means mounted on said board for guiding the thread from said spool to said thread looper, and thread tension means mounted on said board intermediate said guide means and said spool supporting means, said tension means comprising a pair of opposed vertically extending bars for engaging opposite sides of said thread, means for adjusting the relative position of said bars with respect to the direction of the movement of said thread between said bars whereby the tension on said thread may be adjusted, and a second tension means positioned intermediate said first tension means and said guide means, said second tension means comprising a resilient member having one of its ends secured to said board, the other end of said member being provided with a loop to support the thread as said thread enters the guide means.

3. In an embroidery machine having a base, a head supported on said base, a vertical hooked needle reciprocably mounted in said head, a thread looper disposed beneath said base and a thread spool mounting board supported above said head, that improvement which comprises the provision of means for supporting a spool of thread on said board adjacent one end thereof, guide means mounted on said board for guiding the thread to said thread looper, and thread tensioning means mounted on said board between said spool supporting means and said guide means for guiding the thread from said spool supporting means to said guide means, said tensioning means comprising a spring arm having one end mounted on said board and its other end disposed above said board, and spaced loops in the said other end of said spring arm and disposed above said spool supporting means and said guide means and through which the thread passes in moving from said spool supporting means to said guide means.

JOSEPH C. ORRIGO.
